United States Patent Office.

HORACE HOLT, OF NEW YORK, N. Y.

Letters Patent No. 72,042, dated December 10, 1867.

TOOL FOR OPENING FRUIT-CANS.

The Schedule referred to in these Letters Patent and making part of the same.

TO ALL WHOM IT MAY CONCERN;

Be it known that I, HORACE HOLT, of New York, 264 Broadway, in the county and State of New York, have invented a new and improved Tool for Opening Cans; and I do hereby declare that the following is a full, clear, and exact description thereof, which will enable those skilled in the art to make and use the same, reference being had to the accompanying drawing, forming part of this specification, in which drawing—

Figure 1 represents a sectional side elevation of this invention, showing its operation.

Figure 2 is an inverted plan of the same.

Similar letters indicate corresponding parts.

This invention relates to a tool for opening sheet-metal cans, which consists of a pair of tongs provided with an arm, which forms the bearing for a hand-lever, in which a tooth or cutter is secured in such a manner that by clamping the can firmly between the jaws of the tongs, and carrying the hand-lever round while applying the proper downward pressure, a circular or segmental hole is cut into the top of the can, which gives easy access to the contents thereof. The tooth or cutter is placed in an oblique position, which materially facilitates the operation of cutting, and the lever is provided with a raised bearing, close to the tooth, and on its outside, so that the sheet metal, on being cut, is free to rise on the inside of the tooth, and said tooth is prevented from being wedged tight between the edges of the cut.

A represents a pair of tongs, the jaws of which are curved to fit the circumference of the can to be opened, so that by means of said tongs the can may be firmly clamped or held. These tongs are provided with an arm, *a*, of such a form that when the tongs are applied to a can, the end of said arm will extend across the centre of the top of the can; and this arm forms the bearing for a screw or pivot, *b*, which acts as the fulcrum of a hand-lever, *B*. This hand-lever is made of any suitable length, and it carries a tooth or cutter, *c*, which serves to produce the requisite opening in the top, as will be presently explained. The tooth *c* is secured in the hand-lever in an oblique direction, as clearly shown in fig. 1 of the drawing, and to the under surface of the hand-lever, close to the outside of the tooth, is secured a raised bearing, *d*.

In order to open a can, said can is firmly clamped between the tongs *A*, and by suitable pressure the tooth is made to penetrate the top of the can, so that the bearing *d* will rest on the upper surface of said top. The hand-lever is then carried round as far as the arm *a* will allow, and a segmental aperture is cut into the top of the can, which affords easy access to the contents of said can. By the oblique position of the tooth, and by the raised bearing, the operation of cutting is materially facilitated, since the tooth itself causes the inner edge of the cut to curl up, room being afforded by the raised bearing for said edge to rise, and the tooth is prevented from being wedged tight in the cut.

It is obvious that other means might be employed for clamping the tooth-carrying lever down upon the can, besides the tongs shown in the drawing, but I consider the tongs superior to any other device, since they are simple, cheap, and easily handled.

What I claim as new, and desire to secure by Letters Patent, is—

1. A tool for opening sheet-metal cans, composed of a hand-lever, *B*, carrying a tooth, *c*, and connected to tongs *A*, or other equivalent means, capable of clamping said tooth-carrying lever to the can, as set forth.
2. Placing the tooth *c* in an oblique direction, when the same is used in combination with the hand-lever *B* and clamping-device *A*, substantially as and for the purpose described.
3. The raised bearing *d*, in combination with the lever *B* and clamping-device *A*, substantially as and for the purpose set forth.

HORACE HOLT.
